UNITED STATES PATENT OFFICE.

OLIVER J. MOUSSETTE, OF RICHMOND HILL, NEW YORK.

FLUID VALVE.

Application filed February 17, 1921. Serial No. 445,750.

To all whom it may concern:

Be it known that I, OLIVER J. MOUSSETTE, a citizen of the United States, residing at Richmond Hill, Long Island, in the county 5 of Queens and State of New York, have invented a certain new and useful Fluid Valve, of which the following is a specification.

This invention is a valve and is directed, 10 more particularly, to a valve for controlling the flow of fluids under pressure. It is especially adapted for use in connection with oxygen and acetylene tanks of the well known kind employed in the commercial 15 distribution of these gases.

Valves of the general character described are usually formed with a casing or valve housing adapted to screw into the top of a tank and embodying a sealing member normally held to its seat mechanically by a spring, and, also, by the pressure of the gas within the tank. With the valve housing is further associated means to unseat the valve at desired times to allow of the exit of the 25 gas. The means usually employed embodies a hand wheel provided with a threaded stem, which may operate upon the valve directly or through a follower, so that when the hand wheel is rotated, the valve is either 30 forced from its seat against the pressure of the spring and gas or permitted to return to its seat, depending upon the direction of rotation of the hand wheel.

In valves of this character, the sealing 35 members are usually ground to a tight seat or otherwise so constructed as to effect a practically tight seal. However, considerable difficulty has been experienced in precluding the leakage of gas out of the valve 40 casing during the times that the sealing member is unseated and while gas is being drawn off from the tank. The problem of stopping this leakage has been a difficult one, because of the necessity of packing a 45 number of movable parts through the use of glands, washers, stuffing boxes, etc., which are apt to wear out or deteriorate through use. The tendency in the art has been to increase the fixed packing or to improve upon its construction, and while leakage 50 has, in this way, been considerably cut down, I do not know of a single valve on the market wherein leakage is not prevalent.

With the foregoing considerations in mind, the object of the present invention

is a valve which will positively eliminate the leakage referred to. This is accomplished by providing a rubber sleeve which, when the valve is seated, and the tank sealed, preferably lies inoperative within the valve casing. However, when the sealing member is unseated, the sleeve is automatically compressed in one direction and expanded in another, whereby it serves to fill juxtaposed recesses on opposite sides of the joint through which leakage is apt to occur and, in so doing, forms a tight seal to preclude such leakage.

In the preferred construction, the sleeve 70 is made tubular and of rubber and embraces the operating member which acts upon the sealing member of the valve. Annular channels are formed in juxtaposed portions of the operating member and the interior of 75 the valve casing, so that when the hand wheel is operated to open the valve, the operating member is simultaneously depressed, places the rubber sleeve under pressure and compresses it to such extent as to cause it 80 to bulge out in lateral directions and entirely fill the channels, so that leakage in the direction of the hand wheel is positively precluded.

Features of the invention, other than 85 those specified, will be apparent from the hereinafter detailed description and claims, when read in conjunction with the accompanying drawings.

The accompanying drawings illustrate one 90 practical embodiment of the present invention, but the construction therein shown is to be understood as illustrative, only, and not as defining the limits of the invention.

Figure 1 is a central section of a valve 95 embodying the present invention, showing the sealing member seated.

Figure 2 is a view similar to Figure 1, but showing the sealing member unseated.

Figures 3 and 4 are sections on the lines 100 3-3 and 4-4, respectively, of Figures 1 and 2.

Figure 5 is a plan view of the sealing member of the valve; and,

Figure 6 is a section on the line 6-6 of 105 Figure 1.

Referring to the drawings, 1 designates the casing of a valve, provided at its lower end with a threaded portion 2 adapted to be screwed into the tank. Intermediate its 110 ends, the casing has a threaded boss 3 constituting the outlet of the valve and adapted

to receive a suitably threaded connection or coupling. The lower portion of the casting is hollowed out and provides an interior shoulder 4 forming a seat for a sealing member 5, which is normally held to such seat by a spring 6, backed up by a screw plug 7, threaded into the bottom of the valve casing. The sealing member 5 has a stem 8 which is guided in a passage 9 and this 10 passage has a branch duct 10. When the sealing member is unseated, fluid is permitted to flow apass the sealing member, through passage 9, and through the outlet passage 10 to a draw off pipe (not shown) 15 adapted to be associated with the boss 3.

The upper portion of the valve casing is hollowed out and is closed by a screw plug 11, which may be screwed down tight on the casing 1, without washers or gaskets. Holes 20 11^a are provided to permit of the use of a spanner wrench in seating or removing the plug. The lower portion of the plug 11 has a chamber formed therein of polygonal cross section shown as hexagonal, and into this 25 chamber projects the correspondingly shaped portion 13^a of a follower 13. The follower is thus secured against rotation to the plug 11, but is mounted for reciprocation longitudinally of the valve casing, under the 30 impulse of a hand wheel 14.

The hand wheel 14 is provided with a stem 15 mounted for rotation in the plug 11 and precluded from withdrawal by a collar 16, beneath which the stem has a threaded part 35 17. The threaded part 17 projects into a threaded socket in the follower, so that as the hand wheel is rotated, the follower will be shifted longitudinally of the axis of such rotation. In practice the threads of the 40 part 17 are preferably right handed, for reasons hereinafter explained. The follower 13 embodies two portions which are integral with one another, the upper or enlarged portion 13^a of the follower may be termed the 45 head, while the lower or depending smaller portion of the follower may be termed the operating projection and is designated by reference numeral 18.

When the hand wheel 14 is operated, and 50 the follower reciprocated as described, the lower end of the operating projection 18 is adapted for cooperation with the upper end of the stem 8 of the sealing member, so that through rotation of the hand wheel, the seating 55 or unseating of the sealing member may be controlled. When the sealing member is unseated, and gas is flowing through the channel 9 and outlet channel 10, leakage is very apt to occur in an upward direction and 60 around the follower and stem 15 of the hand wheel, and it is to obviate this leakage that the present invention is particularly intended. This end is accomplished by forming a shoulder 19 in the interior of the valve 65 casing above the outlet channel 10 and a co-

acting shoulder 20 on the follower, and by positioning a rubber sleeve or ring 21 around the operating projection 18 of the follower. A portion of the operating projection housed within the rubber sleeve is preferably 70 circumferentially channelled as at 22, and the interior of the valve casing directly surrounding the sleeve is also similarly formed as at 23.

When the sealing member 5 is in normal 75 seated position and the tank associated with the valve, sealed thereby, the parts are as shown in Figure 1 of the drawing, from which it will be noted that the rubber sleeve or ring lies inoperative within the valve casing. However, when it is desired to open or unseal the tank, the hand wheel 14 is rotated to effect longitudinal movement of the follower 13 and move this operating projection 18 into engagement with the stem of 80 the sealing member 5. Continued rotation of the hand wheel will manifestly effect an unseating of the sealing member, thereby permitting the flow of gas through the valve. As the follower is forced down, under the 85 impulse of the hand wheel and stem 15 to unseat the sealing member, considerable pressure will be applied to the rubber sleeve 21, so that it will be compressed and bulged out, both interiorly and exteriorly, and by 90 the time that the sealing member is fully unseated, the bulging of the sleeve will have progressed to such extent that it will entirely fill the annular channels 22 and 23, and in this manner form a tight seal against the 95 leakage of gas upwardly through the valve casing.

As soon as the sealing member is allowed to reseat through retrograde rotation of the hand wheel, the rubber sleeve 21 will return 105 to the position of Figure 1, and its elastic qualities will permit of the reoccurrence of the operations described through an indefinite period. However, should the rubber sleeve so wear, and a new one be advisable, 110 it may readily be installed by merely screwing out the plug 11 and replacing a new sleeve for the one which is worn out.

It has hereinbefore been noted that the 115 threaded part 17 of the stem of the hand wheel is preferably formed with a right hand thread, the purpose of which is to enable the hand wheel to be rotated in directions for opening and closing the valve as are common in the valve art generally. It is usual in valves to turn a hand wheel to the right to shut off the valve and to the left to open the valve. If the screw threaded portion 17 were left handed, the turning of the hand wheel to the right would effect an 120 unseating of the sealing member while the turning of the hand wheel to the left would effect a seating of the sealing member, or an 125 operation just the opposite to that common in valves. As this would lead to mistakes 130

in the operation of the hand wheel by workmen not familiar with the valve, the threaded part 17 is made right handed so that when the hand wheel is turned to the right, the 5 valve will be sealed and when it is turned to the left, the valve will be unsealed. During the operations of the hand wheel, the hexagonal portion of the follower will at all times occupy the hexagonal chamber in the 10 base of the screw plug 11, which will preclude the rotation of the follower and translate rotary movement of the hand wheel into reciprocating movement of the valve for the fulfillment of the functions specified.

15 In the accompanying drawings, the valve is shown as embodying a suitable fuse 24 to release the pressure in the event of fire in the locality of the tank with which the valve is associated, but this fuse forms no part of 20 the present invention.

When the ring or sleeve of rubber or equivalent material is employed in valve construction, for the purpose of producing a tight seal in the manner specified, the employment of additional gaskets, washers and other expedients are rendered unnecessary, and, moreover, the only parts which require accurate machining are the valve seat and the valve or sealing member. This 25 construction greatly economizes the manufacturing of valves and enables their production without precision and in an economical and efficient manner, not before possible in valve construction for controlling fluids under 30 pressure. The valve of the present invention is unusually simple in construction and will, withal, be entirely efficient and practical in its operation.

I am aware that in practice, valves embodying the present invention may be constructed wherein details of structure may be varied from those shown in the drawings, and, accordingly, the present invention is not to be understood as limited to the precise details shown. I consider the invention as broadly novel as is commensurate with the appended claims.

It may be noted, in conclusion, that the changing or renewing of the rubber sleeve 50 of the valve of this invention may be effected while the tank is charged with fluid under pressure as well as when it is empty. This is made possible by the fact that the sealing member 5 is automatically seated by the 55 pressure in the tank as soon as the follower is retracted, thereby enabling the removal of the screw plug and follower without releasing the pressure.

Having thus fully described the invention, what I claim as new and desire to secure by Letters Patent is:

1. A valve embodying a valve casing, a sealing member positioned within the valve casing for normally precluding the flow of 65 fluid therethrough, manually operable means

separate from but adapted to engage with the sealing member for unseating the sealing member, and compressible means positioned in a chamber surrounding the manually operable means but not entirely filling 70 such chamber, said compressible means being free from attachment either to the valve casing or the unseating means for the sealing member and the manually operable means being adapted to compress the compressible means simultaneously with the unseating of the sealing member to cause the compressible means to entirely fill said chamber and form a tight gasket for precluding leakage of fluid from the valve 80 casing.

2. A valve embodying a casing, a sealing member positioned therein for normally precluding the flow of fluid through the casing, a manually operable member free 85 from attachment with the sealing member and mounted for reciprocation within the casing toward and away from the sealing member for the purpose of forcing the sealing member from its seat or permitting the 90 sealing member to seat, an annular member of elastic material loosely positioned in a chamber surrounding the manually operable member and formed partly in the wall of the valve casing and partly in the manually 95 operable member, said elastic member being adapted to be compressed and fill said chamber when the manually operable member is actuated to unseat the sealing member for the purpose of forming a tight packing and precluding leakage of fluid from the valve casing.

3. A valve embodying a casing, a sealing member positioned therein for normally precluding the flow of fluid through the casing, a manually operable member provided with a shoulder and movable toward and away from the sealing member to unseat the sealing member or to permit of the seating thereof, a chamber surrounding a portion of the manually operable member, and an annulus of elastic material positioned within the chamber and engaging with the shoulder of the manually operable member, whereby when the manually operable member is moved to unseat the sealing member, the elastic annulus is compressed and caused to entirely fill the chamber in which it is positioned, thereby precluding the leakage of fluid from the valve casing.

4. A valve embodying a casing, a sealing member associated therewith for normally precluding the flow of fluid through the casing, a follower positioned within the casing, and adapted to engage with the sealing member, a manually operable member having threaded connection with the follower and adapted, when rotated, to impart reciprocation to the follower for the purpose of forcing the sealing member from its seat

or for permitting the sealing member to seat, an annular chamber formed partially within the interior of the valve casing and partially in the follower, and an annular member of rubber positioned within the annular chamber and between a shoulder on the follower and a shoulder in the casing, whereby reciprocation of the follower in a direction to unseat the sealing member 10 serves to place the rubber annulus under compression, whereby it is bulged out and entirely fills the chamber to preclude leakage of fluid therefrom.

5. A valve embodying a casing, a sealing 15 member associated with the casing for normally precluding the passage of fluid through the casing, a follower provided with a polygonal portion, interfitting with the polygonal portion associated with the 20 casing for precluding rotation of the follower, but permitting of longitudinal movement of the follower within the casing, a rotatable operating stem provided with a right hand screw thread cooperating with a

right hand screw thread formed in the follower and adapted to be manually rotated 25 for the purpose of imparting reciprocating movement to the follower, whereby rotation of the operating stem in a counterclockwise direction will effect the unseating of the sealing member, while rotation of the operating stem in a clockwise direction will permit the seating of the sealing member, and a rubber annulus seated in an annular chamber formed partially in the valve casing and 30 partially in the follower with one end of the chamber formed in the follower engaging 35 one end of the annulus and with the opposite end of the chamber formed in the casing engaging the opposite end of the annulus so that the annulus will be bulged out to fill the chamber and form a tight seal to preclude leakage apass the stem when the follower is operated to unseat the sealing member. 40 45

In testimony whereof, I have signed my name to this specification.

OLIVER J. MOUSSETTE.
